UNITED STATES PATENT OFFICE.

ALFONSO HERING, OF BROOKLYN, NEW YORK.

TYPEWRITER ACCENT-KEY ATTACHMENT.

1,365,994.

Specification of Letters Patent. Patented Jan. 18, 1921.

Application filed November 17, 1919. Serial No. 338,519.

To all whom it may concern:

Be it known that I, ALFONSO HERING, a citizen of Chile, South America, and a resident of Brooklyn, in the county of Kings and State of New York, have invented certain new and useful Improvements in Type-writer Accent-Key Attachments, of which the following is a specification.

The principal object of this invention is 10 to provide a simple, effective and inexpensive attachment for typewriters designed to permit the printing of accent marks, as used particularly in foreign composition, without the necessity of back spacing or with regard to the position of the key carrying the 15 accent type.

Another object is in the provision made 20 for quickly and conveniently attaching the device to machines of the Underwood type without having to disarrange the parts.

A further object is in the means provided 25 for making connection to any number of key levers when a plurality of accent marks are desired.

These objects are attained by the novel 30 construction and combination of parts hereinafter described, and shown in the accompanying drawings, forming a material part of this disclosure, and in which:—

Figure 1 is a partial sectional and side elevational view of the operative parts of the machine, showing the intercepting device 35 constituting the invention.

Fig 2 is a similar view of the same in operating position.

Fig. 3 is a rear elevational view of the interceptor, rocker bar and connections.

Fig. 4 is an end elevational view of the same, and,

Fig. 5 is a perspective view of the interceptor plate and lever.

Referring to the drawings in detail, the numeral 10 designates a typewriter key lever pivoted at the point 12 and provided with a slot 14, engaged by the hook 15 of the operating pull wire 16, the upper end of which is held in an opening in the U shaped clamp 17 and prevented from dropping out by an integral hook 18, the clamp 17 being adjustably secured lengthwise of the rocker bar 20 by the binding screw 19.

Rigidly attached to the rocker bar 20, in a relatively central position, is an eye 22 having a rearwardly extending arm 23, turned angularly, as at 24, parallel to the bar 20, and pivotally secured upon it, by the lugs

25 and 26, is an interceptor 28 in register and contactable with the dog rocker 31 of the machine.

The interceptor 28 is reinforced by extending the lug 26 to its lower edge, and also thickened at the top by a reentrantly turned clip portion 29.

The interceptor is held in a normally vertical position, due to its engagement with the bar 20, by the torsional effect of the coiled spring 32, secured to the bar at one end and engaged by its hooked end 33 with the support 34, the latter being provided with an opening to receive the rod 20 and at its opposite end with an angular outturned foot for securing it to the frame of the machine. A similar support 35 is provided to receive the opposite end of the bar 20, which is retained in position between the supports 70 by the collar 36 and spring 32.

The pivoted interceptor 28 is mounted with the narrow upper portion 29 between the universal bar 30 and the dog rocker 31, the escapement adjusting screw 38 being 80 ground flush with the dog rocker on its adjacent side to allow the interceptor to move freely when in contact.

The lower portion of the interceptor acts as a dog rocker lock, the spring 32 always 85 holding the interceptor in normal position, except when the accent keys are depressed, the connecting wire 16, which engages the bar 20, being adjusted to aline with accent key levers 10, and if a plurality of accent 90 keys are required, additional connecting wires and clamps may be placed upon the bar 20 and connections made as described.

The flanged bases or feet of the two supports 34 and 35, holding the bar 20, are substituted for the original ribbon shaft actuator support bearing caps by taking out the holding screws and exchanging the parts.

In operation, upon depressing the key, carrying the accent character, the rocking 100 bar 20 is partially rotated by the hooked wire 16 connecting it with the key lever, which action lowers the interceptor, thereby preventing the carriage from moving a space by interposing the interceptor between the 105 dog rocker and the tie bar 40 of the escapement frame, the downward movement of the interceptor being limited by the adjusting screw 41.

At the same time, as shown in Fig. 1, the 110 interceptor is in position so that when the universal bar 30 is operated that it will

make contact with the interceptor and through it tilt the dog rocker, but when the interceptor is lowered, by action of the accent key lever, as shown in Fig. 2, the universal bar cannot reach the dog rocker, the screw point having been removed, thus rendering the escapement temporarily inoperative.

Having thus described my invention, what I claim as new and desire to secure by Letters Patent, is:—

1. A non-feed accent key attachment comprising in combination with a typewriter having a tie bar, a universal bar, an escapement, including a dog rocker carrying a rigid and loose dog, accent type bars, and keys for operation thereof, of an interceptor adapted to make contact with said dog rocker, and means engaged with one or more of said accent type bars for moving said interceptor into the path of motion of said dog rocker relative to said tie bar whereby it is prevented from operation and coincidentally out of the path of travel of said universal bar.

2. A non-feed accent key attachment comprising in combination with a typewriter having an escapement including a dog rocker carrying a rigid and a loose dog, accent type bars, operating keys, a tie bar adjacent said escapement and a universal bar, of an interceptor interposed between said dog rocker and universal bar when transmitting motion to the dog rocker, and means integral with said interceptor actuated by said accent type bars for retracting said interceptor when said bars are depressed and for blocking said dog rocker against said tie bar.

3. A non-feed accent key attachment comprising, in combination with a typewriting

machine having a tie bar, an oscillating dog-rocker and key operated mechanism for imprinting accents, of a rock-shaft supported transversely in said machine, operative connections between said rock-shaft and said key mechanism whereby the rock-shaft may be partially rotated, means for returning said rock-shaft to its normal position upon the release of said key mechanism, and an interceptor actuated by said rock-shaft, said interceptor being adapted to positively prevent the normal movement of said dog-rocker when said rock-shaft is moved by said accent printing mechanism by intercepting between the lower portion of said dog rocker and said tie bar.

4. A non-feed accent key attachment comprising in combination with a typewriting machine having an oscillating dog rocker carrying a rigid and a loose dog, and a key actuated mechanism for printing accents, of a rock-shaft arranged transversely in said machine, supports for said shaft attached rigidly to said machine, a torsional spring fixed respectively to said shaft and to one of said supports, clamps adjustable longitudinally on said shaft, links engaging said clamps and the accent key levers, an eye rigid on said shaft, an arm formed with said eye, said arm having an angular outer end, an interceptor plate pivoted on said angular end, and reinforcements formed on said interceptor plate, said plate being adapted to move into contact with said dog rocker and prevent it from operating upon the depression of said accent key levers.

In testimony whereof I have signed my name to this specification.

ALFONSO HERING.
